US0D1086485S

(12) **United States Design Patent** (10) **Patent No.:** **US D1,086,485 S**
(45) **Date of Patent:** **** Jul. 29, 2025**

(54) **LIQUID SAMPLE COLLECTOR**

(71) Applicant: **Hangzhou Biotest Biotech Co., LTD.**,
Hangzhou (CN)

(72) Inventors: **Shujiang Wu**, Hangzhou (CN); **Qihui Zhao**, Hangzhou (CN); **Hui Geng**, Hangzhou (CN); **Liang Hong**, Hangzhou (CN)

(73) Assignee: **HANGZHOU BIOTEST BIOTECH CO., LTD.**, Hangzhou (CN)

(**) Term: **15 Years**

(21) Appl. No.: **29/880,236**

(22) Filed: **Jul. 19, 2023**

(30) **Foreign Application Priority Data**

Jun. 26, 2023 (CN) 202330394033.9

(57) **CLAIM**

The ornamental design for a liquid sample collector as shown and described.

DESCRIPTION

FIG. 1 is a perspective view of a liquid sample collector showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is another perspective view thereof.

1 Claim, 8 Drawing Sheets
